UNITED STATES PATENT OFFICE.

HOWARD S. MOUNTFORD, OF ALGONA, IOWA.

INTAKE-MANIFOLD FOR INTERNAL-COMBUSTION ENGINES.

1,098,915.

Specification of Letters Patent. Patented June 2, 1914.

Application filed December 28, 1912. Serial No. 739,104.

To all whom it may concern:

Be it known that I, HOWARD S. MOUNTFORD, a citizen of the United States, residing at Algona, in the county of Kossuth and State of Iowa, have invented certain new and useful Improvements in Intake-Manifolds for Internal-Combustion Engines, of which the following is a specification, reference being had therein to the accompanying drawing.

This invention relates to intake manifold heaters and has for its object the production of a simple and efficient means for heating the intake for an explosive engine in such a manner as to cause an efficient combustion within the explosive cylinder.

Another object of this invention is the production of a simple and efficient intake manifold casting wherein the exhaust gases from the engine may be passed around the intake pipe in such a manner as to heat the intake gas to a sufficient temperature to cause an efficient explosion within the cylinder of the engine.

With these and other objects in view, this invention consists of certain novel constructions, combinations and arrangements of parts, as will be hereinafter fully described and claimed.

In the accompanying drawings:—Figure 1 is a side elevation of a series of cylinders showing the intake manifold casting applied thereto. Fig. 2 is a view of the intake manifold casting from the opposite side to that as illustrated in Fig. 1. Fig. 3 is an end view of the intake manifold casting. Fig. 4 is a central sectional view of the intake manifold casting taken on line 4—4 of Fig. 1, looking in the direction of the arrow.

By referring to the drawings, it will be seen that 1 designates the engine which is provided with the usual exhaust manifold casting 2 and the usual carbureter 3 is connected to the cylinders of the engine by means of the intake manifold casting 4. This intake manifold casting 4 comprises a lower neck portion 5 which connects directly to the carbureter 3 and the casing is also provided with a pair of outlet openings or passageways 6 which connect directly with the cylinders of the engine. The casting 4 comprises a substantially V-shaped body having a centrally located intake passageway 7 formed therein, and this passageway 7 is so formed as to extend centrally of the com-

partment 8 formed by the outer casing 9 of the casting 4. The intake or supply pipe 7 is formed within the casting 4 so as to constitute a substantially T-shaped structure 60 having laterally extending ends 10, as illustrated in dotted lines in Fig. 1 communicating with the discharge passageways 6 which supply the combustion or heated gases to the cylinders. It will be seen by carefully considering Figs. 1 and 4 that a pocket 11 is formed upon each side of the intake passageway or supply pipe 7 and an exhaust supply pipe 12 is directly connected to one of the compartments or pockets 11 by means of an angle pipe 13. This exhaust supply pipe 12 is connected to the exhaust manifold 2 by means of a coupling 14 and a valve 15 is carried by the pipe 12 so as to control the supply of exhaust from the exhaust 75 manifold casing 2 to the intake manifold casting 4. An exhaust discharge pipe 16 is connected to the opposite pocket 11 by means of the angle connection 17 as clearly illustrated in Figs. 1 and 4, and this exhaust discharge pipe 16 allows the exhaust, after having passed through the intake manifold casing, to be discharged therefrom.

From the foregoing description, it will be seen that a very simple and efficient device 85 has been produced whereby the exhaust from an engine of the explosive character may be utilized for the purpose of heating the intake gases as the same pass through the intake manifold casting. It will also be seen 90 that in view of the fact that the intake manifold casting 1 is provided with an integrally formed pipe within the body so as to produce pockets upon each side and also a passageway for the heated gases to pass 95 around the intake pipe, a very efficient means has been produced for heating the intake gases in view of the fact that the maximum amount of heating surface is placed within the intake manifold casting 4. 100

The valve 15 is operated by means of the handle 18 so as to cut off the supply of exhaust from the exhaust manifold casing 2.

From the foregoing description, it will be seen that owing to the construction of the present device the operator will be enabled to use a lower gravity fuel than is ordinarily used by reason of the more efficient combustion explosion which is obtained thereby.

Having thus described the invention, what 110 is claimed as new, is:—

1. In a device of the class described, the

combination with an explosive engine, an exhaust manifold casting and an intake manifold casing, said intake manifold casting provided with a substantially V-shaped body having a reduced neck at its inlet end, said intake manifold casting also provided with an integrally formed, centrally arranged intake supply pipe having a flaring outlet end that terminates in laterally extending ends, said casting provided with discharge openings for connecting with an explosive engine whereby fuel may be supplied to said explosive engine, said intake manifold casting provided with a compartment 10 extending around said intake supply pipe formed within said casting, and means connecting said compartment with said exhaust manifold casting whereby heated gases may be passed from said exhaust manifold casting into said compartment.

2. In a device of the class described, the combination with an engine, an exhaust manifold casting, of an intake manifold casting comprising a substantially V-shaped body

provided with a reduced inlet end, said intake manifold casting provided with an integral comparatively narrow supply pipe formed therein that flares outwardly from its inlet and terminates in laterally extending ends, said intake manifold casting provided with discharge openings in said laterally extending ends, said casting provided with a compartment that surrounds said supply pipe, a pipe connecting said exhaust manifold casting with said compartment for supplying heated gases from said exhaust manifold casting into said intake manifold casting, valve means for controlling the passage of heated gases through said pipe, and an exhaust pipe connected to said compartment for discharging heated gases therefrom.

In testimony whereof I hereunto affix my signature in presence of two witnesses.

HOWARD S. MOUNTFORD.
